UNITED STATES PATENT OFFICE.

FRANK ROBINSON, OF CHICAGO, ILLINOIS.

SPARK-PLUG.

1,242,375.

Specification of Letters Patent.

Patented Oct. 9, 1917.

Application filed January 15, 1917. Serial No. 142,365.

To all whom it may concern:

Be it known that I, FRANK ROBINSON, a citizen of the United States, and a resident of the city of Chicago, in the county of Cook and State of Illinois, have invented certain new and useful Improvements in Spark-Plugs; and I do hereby declare that the following is a full, clear, and exact description of the same, reference being had to the accompanying drawings, and to the numerals of reference marked thereon, which form a part of this specification.

This invention relates to an improved form of spark plug constructed to be practically self-cleaning, and having its parts so arranged that those parts liable to become fouled or damaged may be readily removed for cleaning or replacement without requiring the complete removal of the entire plug from an engine cylinder in which it is mounted.

It is an object of this invention to provide an improved form of spark plug adapted to permit removal of certain of the parts thereof for cleaning without detachment of the entire plug from a cylinder in which it is connected.

It is also an object of this invention to construct a spark plug having a core made up of an insulating member and a metallic member adapted to be readily removed and cleaned without detaching the entire plug from its mounting.

It is a further object of this invention to provide a spark plug wherein a combustion chamber is formed by a tubular insulating core member having an enlarged recess therein registering with the opening in a cylindrical metallic core member, and in which the core members are removably locked in a metallic casing by a lock nut permitting cleaning of the parts liable to become fouled without detachment of the entire spark plug from a cylinder on which it is mounted.

It is furthermore an important object of this invention to construct a spark plug in which a combustion chamber is formed by two core members removably locked one upon the other within a shell, with the lower core member seated to hold one of the ignition terminals in position to form a suitable spark gap between a second ignition terminal associated with the upper core member, said terminals being practically self-cleaning, and arranged for removal from the

plug shell without detachment of the entire plug from an engine cylinder on which the plug is mounted.

It is finally an object of this invention to construct a spark plug wherein the core member is made up of a number of parts, each having a terminal associated therewith, said core parts and terminals adapted to be readily removed for cleaning or repair without detachment of the spark plug from its mounting.

The invention (in a preferred form) is illustrated in the drawings and hereinafter more fully described.

On the drawings:

Figure 1 is a side elevational view of a spark plug embodying the principles of my invention.

Fig. 2 is a top plan view thereof. 75

Fig. 3 is a section taken on line 3—3 of Fig. 2.

Fig. 4 is a section taken on line 4—4 of Fig. 3.

Fig. 5 is a section taken on line 5—5 of Fig. 3. 80

Fig. 6 is a central vertical section taken through the knurled conductor cap.

Fig. 7 is a side elevational view of the spark plug having the conductor cap replaced by a lock nut and a priming mechanism, with parts shown in section. 85

As shown on the drawings:

The reference numeral 1, indicates a spark plug sleeve or shell, having an externally threaded plug 2, integrally formed on the lower end thereof, and an internally threaded integral hexagonal portion 3, formed on the upper end thereof affording a nut for receiving a wrench engaged therewith to permit the spark plug sleeve to be rigidly but removably engaged into a suitable threaded aperture formed in an engine cylinder.

Seated within the sleeve 1, and bearing upon the upper end of the plug 2, is a flat steel ring plate stamping 4, having a diametrically disposed cross-bar 5, integrally formed therein by cutting away parts of the material, said cross-bar being formed with an enlarged middle portion 6, having an aperture therein. Mounted upon the enlarged portion 6, of the cross-bar, and rigidly secured thereto by means of a rivet 7, or other suitable means projecting upwardly through the aperture in said enlarged portion, is an axially disposed vertical spindle

or conductor 8, formed with an enlargement 9, near its upper end to hold a downwardly curved baffle plate 10, in position. Said baffle plate 10, has an aperture formed centrally therein to permit the upper reduced end of the spindle 8, to project upwardly therethrough to afford a spark terminal or tip 11.

Fitting within the lower half of the sleeve 1, and bearing upon the ring plate 4, is a metal cylindrical lower core member 12, extending upwardly to about the height of the spindle enlargement 9. The lower core member 12, forms the lower half 13, of a combustion chamber in which the spindle and baffle plate are located, as clearly shown in Fig. 2. Also fitting within said sleeve 1, in the upper half thereof, is a relatively long tubular open core member 14, of porcelain 20 or other suitable insulating material projecting upwardly out of the sleeve 1, and having an enlarged portion or base 15, integrally formed at the lower end thereof which fits snugly against the inner walls of said shell 1, and seats upon the upper end of the lower metal core member 12. The enlarged core portion 15, has formed therein the upper half 16, of the combustion chamber, affording a chamber into which the spark terminal 30 or terminal tip 11, projects to within a short distance of the lower outwardly flanged spark terminal end 17, of a conductor tube 18, mounted within the tubular upper core member 14, and having its upper end exteriorly threaded, as denoted by the reference numeral 19, which projects upwardly beyond the upper end of said core member 14.

Removably threaded upon the upper threaded end 19, of the conductor tube 18, 40 is a lock nut 19^a, and a knurled terminal connector cap 20, for clamping a conductor wire (not shown) in position around the upper end of said conductor tube. To form an air-tight fit at the upper end of the tube 18, the connector cap 20, has integrally formed on the interior thereof, a downwardly directed stem or finger 21, which fits into the upper end of the opening in said tube when said cap 20, is threaded thereon. 45 For removably holding the ring plate 4, the lower metallic core member 12, and the upper insulating core member 14, in position within said sleeve 1, a threaded gland or lock nut 22, is threaded into the upper hexagonal end 3, of the sleeve, and presses against suitable packing, resting on the upper end of the enlarged core portion 15, to clamp said parts in place sealed and properly aligned within the sleeve.

60 In the form of spark plug shown in Fig. 7, the construction is similar to that of the spark plug shown in Figs. 1 to 6, with the exception that the connector cap 20, is replaced by a knurled lock nut 23, and a 65 priming mechanism 24, both threaded upon

the upper projecting threaded end of the conductor tube 18. An ignition wire or conductor may be readily attached to the spark plug around the tube 18, and between the lock nut 23, and the priming mechanism 24. 70

It will be noted from the construction of the spark plug as described, that the various parts within the sleeve of the spark plug may be readily removed or replaced for cleaning or repairs without requiring the 75 complete removal of the spark plug from an engine cylinder to which it is attached. I am also aware that various details of construction may be varied through a wide range without departing from the principles 80 of this invention, and I therefore do not purpose limiting the patent granted otherwise than necessitated by the prior art.

I claim as my invention:

1. In a spark plug of the class described, 85 a sleeve member adapted to be threaded into the wall of an engine cylinder, chambered insulating and metallic core members removably mounted therein to register with one another to form a combustion chamber, 90 and spark terminals projecting into said combustion chamber to within a short distance of one another to form a spark gap.

2. In a spark plug of the class described, 95 a sleeve adapted to be threaded into the wall of an engine cylinder, a lower chambered metallic core member seated therein, an upper chambered insulating core member within said sleeve and mounted upon said lower core member with the chambers registering 100 with one another to form a combustion chamber, a spark terminal associated with each of said core members projecting into the combustion chamber to form a spark gap between adjacent ends thereof, and 105 means for removably locking said core members within said sleeve.

3. In a spark plug of the class described, 110 a sleeve, a chambered metallic core member seated therein, a chambered insulating core member within said sleeve resting upon said metallic core member, said core members arranged with their chambers registering with one another to afford a combustion chamber, 115 terminals projecting into said combustion chamber to afford a suitable spark gap therebetween, means mounted on one of said terminals to keep said terminals clean, and a gland threaded into said sleeve for removably holding said core members in position. 120

4. In a spark plug of the class described, 125 an apertured sleeve having a passage therein, a chambered metallic lower core member seated therein, a passaged upper insulating core member in said sleeve resting upon said lower core member, an enlarged portion integrally formed on said upper core member having a chamber therein to register with the chamber in the lower core member to afford a combustion chamber, a conductor 130

- tube in said passaged upper core member projecting into said combustion chamber to afford a spark terminal, spark terminal means held in position within said combustion chamber by said lower core member, said spark terminal means projecting upwardly to a point below the spark terminal of said conductor tube to form a spark gap, a lock nut on said tube to hold the same in position, a cap adapted to be removably threaded upon the upper end of said conductor tube affording an air tight closure, and a gland threaded into said sleeve and sealingly contacting the enlarged portion of said upper core member for removably holding the spark plug parts within said sleeve.
5. In a device of the class described, a sleeve, a metal plate stamping seated therein, a metallic lower core member mounted thereon having a chamber therein, a spark terminal rigidly secured upon said metal plate stamping projecting upwardly into said chamber, baffle cleaning means mounted thereon, an insulating upper core member in said sleeve resting upon said lower core member and having a chamber therein registering with the chamber in said lower core member to afford a combustion chamber, a second spark terminal associated with the insulating upper core member projecting into said combustion chamber to a point above the first mentioned spark terminal to afford a spark gap, and means for remov-
- ably locking said core members within said sleeve. 35
6. A spark plug comprising a shell, a chambered lower metallic core member therein, a chambered upper insulating core member within said shell registering with said lower core member to form a combustion chamber, 40 and a spark terminal associated with each of said core members projecting into said combustion chamber to within a short distance of one another to form a spark gap.
7. A spark plug comprising a shell, and a 45 core having a combustion chamber therein removably mounted within said shell and comprising a lower metallic core member and an upper insulating core member, registering with one another to form said combustion chamber.
8. In a device of the class described, a sleeve, a lower and an upper core member seated therein, a combustion chamber formed by said core members, spark terminals projecting into said combustion chamber, and means for removably locking said core members within said sleeve. 50
- 55
- In testimony whereof I have hereunto subscribed my name in the presence of two sub- 60 scribing witnesses.

FRANK ROBINSON.
